CLAIM

The ornamental design for a couch, as shown and described.

DESCRIPTION

FIG. 1 is a perspective view of a couch showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a perspective view thereof in an alternate configuration.

The dash-dash broken lines indicate the sewing threads of the couch and form part of the claimed design. The dot-dashed broken lines depict portions of the couch, which form no part of the claimed design.
